BLOOD GROUPING TEST SLIDE

Jack R. Rubin, 1433 Franklin St., Santa Monica, Calif.
90404, and Arnaldo Peralta, 1426 Crestview Court,
Los Angeles, Calif. 90024

Filed Dec. 12, 1968, Ser. No. 14,945

Term of patent 14 years

Int. Cl. D24—02

U.S. Cl. D16—1

Fig. 1

Fig. 2

Fig. 3

Fig. 5

Fig. 6

Fig. 8

Fig. 7

FIG. 1 is a perspective view of a blood grouping test slide, the broken lines illustrating the tiered relationship of the slides are shown for illustrative purposes only;

FIG. 2 is a top perspective view of the blood grouping test slide;

FIG. 3 is a top plan view thereof;

FIG. 4 is a front elevation thereof;

FIG. 5 is an end elevation as seen from the left of FIG. 4;

FIG. 6 is an elevation as seen from the right of FIG. 4; and

FIG. 7 is a bottom plan view of a modified embodiment of the slide shown in FIG. 1; and

FIG. 8 is a top plan view thereof.

The broken lines are shown for illustrative purposes only and do not form part of the claim.

We claim:

The ornamental design for blood grouping test slide, substantially as shown and described.
